(57) **CLAIM**

The ornamental design for a manual control device, as shown and described.

DESCRIPTION

FIG. 1 is an isometric view of a manual control device, showing our new design;

FIG. 2 is a front side view thereof;

FIG. 3 is a rear side view thereof;

FIG. 4 is a right side view thereof;

FIG. 5 is a left side view thereof;

FIG. 6 is a top view thereof; and,

FIG. 7 is a bottom view thereof.

The broken lines are for illustration purposes only and form no part of the claimed design.
